(57) **CLAIM**

The ornamental design for a coat hook door stop, as shown and described.

DESCRIPTION

FIG. 1 is a top, front, left side perspective view of a coat hook door stop according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The coat hook door stop is shown with long dash-short dash break lines representing a symbolic break in its length, with the brackets adjacent the dashed break lines forming no part of the claimed design, and instead indicate that the appearance of any portion of the coat hook door stop between the dashed break lines forms no part of the claimed design. The short dash-short dash broken lines show portions of the coat hook door stop that form no part of the claimed design.

1 Claim, 5 Drawing Sheets
